UNITED STATES PATENT OFFICE.

HENRY S. BOOTH, OF MANCHESTER, ENGLAND.

AERIAL MACHINE.

No. 907,310.

Specification of Letters Patent. Patented Dec. 22, 1908.

Application filed July 27, 1906. Serial No. 328,132.

To all whom it may concern:

Be it known that I, HENRY S. BOOTH, British subject, and resident of Manchester, county of Lancaster, England, have invented 5 certain new and useful Improvements in Aerial Machines, of which the following is a specification.

This invention relates to means for raising 10 propelling and controlling the equilibrium of a machine in the air, it may be used either with or without an aerostat.

The invention consists essentially in constructing the machine with (a) one, two or more sets of shafts or spindles at each side, 15 parallel to the longitudinal axis of the machine, the sets of spindles on the one side being rotated in the opposite direction to the sets of spindles on the other, each shaft or spindle being fitted with one or more wings 20 or air blades constructed to adapt themselves to the angle of resistance to the air which produces the best upward and forward effect. (b) Means for greatly accelerating the 25 velocity of the wings or air blades during all or part of their downward rotation. (c) Clutches or differential gearing fixed between the prime motor and the sets of shafts or spindles so that without interfering with the speed of the motor one of the sets of 30 shafts or spindles can be stopped, or the speed of rotation of the sets of shafts or spindles on either side of the machine can be retarded and the speed of the sets of shafts or spindles on the other side correspondingly 35 increased.

The invention will be fully described with reference to the accompanying drawings.

Figure 1. End elevation. Fig. 2. Plan. Fig. 3. Part of end elevation enlarged. Fig. 40 4. Part of plan enlarged. Fig. 5. End elevation enlarged (of driving mechanism). Fig. 6. Side elevation of same. Fig. 7. Plan. Fig. 8. End elevation of another arrangement of driving mechanism.

45 In carrying out the invention I construct a frame A of any suitable light construction in which I mount two sets of shafts or spindles B B' carrying wings or air blades C C' one set on each side of the longitudinal 50 axis of the machine indicated by the arrow x-x. The spindles B and B' are mounted in suitable bearings b parallel with the longitudinal axis (x-x) of the machine the spindles B on one side being rotated in one direction and the spindles B' on the other

side in the reverse direction. To each of the spindles B B' a rigid arm D is attached towards the forward end of the frame A, and an elastic arm D' towards the rear end of the frame to which sail cloth or suitable material is attached to form the wings C C'. The extremity of the arm D is connected with the extremity of the arm D' by a wire or bar d. The wings or air blades C C' are attached to the arm D to the spindle or shaft 60 and to the wire d with the back edge adjacent to the arm D' free to adjust itself to the wind pressure. The rear arms D' are set at an angle with relation to the forward arms D such that when the arms D' are horizontal when moving downward and exercising pressure in a forward direction the arms D will have passed the horizontal and be inclined in a downward direction.

I prefer to use several spindles B B' and 75 wings C C' on each side of the machine as shown in Figs. 1 and 2 as I find that by reducing the radius of the wings and increasing their number the power required to control the machine is very substantially 80 reduced, but if desired a single wing might be used at each side of the machine. The spindles B B' are driven from the shafts E E' by chains e e' and are geared together by driving chains d' at both ends to rotate 85 simultaneously, the motive power being obtained from any suitable motor and transmitted through the driven wheel F by chain or other gear. The speed of the wings C C' is accelerated during all or a portion of their 90 downward movement by any suitable construction of mechanism. The desired acceleration may be brought about by the employment of elliptical gearing which will greatly 95 accelerate the speed at one part of the revolution. By employing a train of elliptical gearing G G' G² the desired acceleration can be obtained while employing wheels which are but slightly modified from circular. One wheel G of the train of elliptical wheels is on 100 the shaft H the second elliptical wheel on the shaft H' and the third wheel on the shaft H². The shaft H² is divided into three parts h h' h² the central part h being free to rotate in either direction. The part h' is 105 driven by the elliptical wheels in one direction and the part h² is driven in the other direction by a chain from the wheel g' on the shaft H' to the wheel g² on the shaft h². An arm K is fixed on the shaft h' which en- 110

gages with a corresponding loose arm K' on shaft h; a spring h is placed between the arm K and the shaft h' to form a buffer to lessen the shock when the arms meet. A corresponding arrangement of arms L L' and spring l is fixed between the shafts h and h² for the purpose of reversing the motion. The arms K' and L' are loose upon the central part h of the shaft H² upon which two sliding clutches M M' are fitted either of which can be thrown into engagement with its respective arm and so convey motion to the shaft h. By throwing both clutches M M' out of gear the central shaft may be stopped without stopping the motor. When the clutch M is in engagement with the arm K' the wings C C' are driven to exercise pressure in a forward direction and when the clutch M' is in engagement with the arm L' the wings are driven to exercise pressure in the reverse or backward direction. The motion is transmitted from the shaft h by the differential gearing N to the shafts O' O² E E'. The desired acceleration may be brought about by the employment of suitable springs which will greatly accelerate the speed of the driven shaft. The shaft H³ is driven from the shaft H by a sprocket wheel h³ on the shaft H, a sprocket wheel h⁴ on the shaft H³ and a driving chain h⁵. One of the sprocket wheels preferably the driven wheel h⁴ is constructed with a free wheel action so that the shaft H³ may rotate at a greater speed than the driving shaft H. On either one or both ends of the shaft H³ are mounted cranks R to which springs S are connected by connecting links or rods s. On the upward stroke the spring or springs S are extended and when the crank passes the top center the full effect of the spring comes into play, and greatly accelerates the crank on the downward stroke. The springs may be arranged in any other convenient manner for the same purpose. The motion is transmitted from the shaft H³ by the differential gearing N to the shafts O' O² E and E'.

The differential gearing consists of a pinion n which drives a similar pinion n' on the line of shaft O loose bevel wheels n² which are mounted on the spindles of n' and gear with the bevel wheels o o' on the shafts O' and O². The shaft O on which the pinion n' is fixed is journaled in the ends of the shafts O' and O² and the arrangement of differential gearing will drive the shafts O' O² at a uniform speed when the loads are equal or one shaft slower and the other shaft correspondingly quicker when the loads are unequal. At the end of shaft O' a pair of bevel wheels e² e³ drive the shaft E at right angles and at the end of shaft O² a pair of bevel wheel e⁴ e⁵ drive the shaft E' at right angles. The shaft E is on the opposite side of the line of shaft O to shaft E' and is rotated in the opposite direction. The bevel wheels

e³ and e⁵ are each provided with a brake so that the motion at either side may be retarded and at the other side correspondingly increased.

In place of the differential gearing the bevel wheels e² e⁴ could be driven by clutches. When either clutch is disengaged the motive power would be transmitted to the wings on the opposite side of the machine through the clutch still engaged on that side.

The acceleration of the speed of the wings C on the downward part of their rotation may be effected in an alternative arrangement by jointing them to the spindles and holding them in position by springs which by the rotation of the spindles are compressed or extended and released at the point at which the wings will exercise the greatest downward pressure on the air therefore giving greater velocity to the wings at the time of release than the spindles would impart. Or the desired acceleration may be effected by springs or cylinders and pistons in which force is generated or accumulated during a portion of the revolution of the spindles and released at any desired point to accelerate the speed of the spindles and through them the wings, in the manner described in the specification of my former application for patent Serial No. 205,052 filed 26th April, 1904.

The mechanism would be operated as follows:—When the clutch M is in action the arm K would engage with the arm K' when the wings or air blades were rotating in a downward direction and force them downwards with great rapidity and the power would be exercised in giving an upward and forward motion to the machine to which the mechanism was attached. During the upward rotation of the wings or air blades the effect of the train of elliptical wheels would reduce the speed to a point at which the pressure the wings or air blades would exercise against the air would be very slight.

By applying the brake on one of the rims of the bevel wheels e³ e⁵ the speed of rotation of the wings or air blades on one side of the machine can be retarded and by the action of the differential gearing the speed of the wings or air blades on the other side correspondingly increased thus providing an instantaneous means for controlling the equilibrium of the machine.

By putting the clutch M' into operation the wings or air blades would be operated in the opposite direction the arms would be arranged to give the greatest thrust to the wings or air blades when they were rotating in a downward direction and the force would be thus applied in raising the machine or in maintaining its elevation and at the same time retarding its forward motion.

The invention may be used in conjunction with air planes to assist in supporting the

machine and screws or blades for propelling it, and it may also be used with or without an aerostat.

What I claim as my invention and desire 5 to protect by Letters Patent is:—

1. In an air ship or flying machine the combination with a central frame work A, of a set of wings B placed at one side of the longitudinal axis of the machine, a set of 10 wings B' placed at the other side of the longitudinal axis of the machine corresponding shafts b to which the wings are affixed means by which a rotary motion is imparted to each of the shafts and wings 15 and means by which an accelerated movement is given thereto on the downward beat of the latter substantially as described.
2. In an air ship or flying machine the combination with a central frame and sets of 20 wings at either side thereof, of differential gearing to control the equilibrium of the machine substantially as described.
3. In air ship or flying machine the combination with the central frame and set of 25 wings at either side thereof to which a rotary movement is imparted, of elliptical gearing by which the speed of the wings is accelerated during the downward beat of same substantially as described.
4. In an air ship or flying machine the combination with a central framework A, of 30 a set of wings B placed at one side of the longitudinal axis of the machine a set of wings B' placed at the other side of the longitudinal axis of the machine, corresponding shafts or spindles b to which the wings are affixed and to which a rotary motion is imparted, means by which an accelerated movement is given to the shafts b and the wings B B' on the downward beat of the latter, and differential gearing N by which the equilibrium of the machine is controlled substantially as described.
5. In an air ship or flying machine the combination with a central frame work A, 45 of a set of wings B placed at one side of the longitudinal axis of the machine, a set of wings B' placed at the other side of the longitudinal axis of the machine, corresponding shafts or spindles b to which the wings are af- 50 fixed and to which a rotary motion is imparted, elliptical driving gear G G' G² by which an accelerated movement is given to the shafts b and the wings B B' on the downward beat of the latter, and differential gearing N by which the equilibrium of the machine is controlled substantially as described.

In witness whereof, I have hereunto signed my name in the presence of two subscribing witnesses.

H. S. BOOTH.
